UNITED STATES PATENT OFFICE.

ABNER M. ROSEBRUGH, OF TORONTO, ONTARIO, CANADA.

MECHANICAL-TELEPHONE SYSTEM.

SPECIFICATION forming part of Letters Patent No. 389,601, dated September 18, 1888.

Application filed October 21, 1885. Serial No. 180,540. (No model.) Patented in England August 22, 1885, No. 9,962.

To all whom it may concern:

Be it known that I, ABNER M. ROSEBRUGH, a subject of the Queen of Great Britain, and a resident of Toronto, in the Province of Ontario, Canada, have invented certain new and useful Improvements in Telephones, of which the following is a specification.

My improvements relate to a system of mechanical telephones, or, as I prefer to term them, "speaking-tube telephones," and to arrangements whereby the said systems are rendered available for exchange purposes, for which I have received British Letters Patent No. 9,962, dated August 22, 1885.

One part of my improved system relates to the construction of the line, the object being to diminish or eliminate the harsh metallic vibrations incident to such telephones as now used. The improvement consists in using cord for the whole or part of the line, and preferably using cord that has been saturated in oil to make it more durable. In cases where wire is used the connections with the telephones are made with cord, and cord is also used in parts of the line where said line is made to deviate from a straight line. The cord is preferably accompanied by a fine wire to be used for electrical signaling, and said fine wire may be wound around or form part of said cord; and in cases where the line is divided into sections, as herein described, the fine wire accompanying said cord is made to make metallic connection with the all-wire section, so as to establish metallic connection between the two telephones.

Another point in my system is the mounting of the diaphragm. This may be either of stiff material—such as ebonite, sheet metal, mica, slate, or wood—or of some flexible material—such as silk, felt, parchment, straw, &c.—strained or affixed over or upon or within a ring-casing or other rigid frame; but in either case I mount it by an elastic or yielding cushion—such as a ring of india-rubber interposed between the said diaphragm or frame thereof and the box, board, casing, or mouth-piece in which it is mounted. I find that the said cushion contributes to the good acoustic qualities of the instrument and eliminates lateral vibration. The instruments may be placed against the wall or other support in the room of the house or office of the person who wishes to use

it, the line being brought through a suitable aperture in the wall; or, where more convenient, I place the instrument itself outside the house, affixing it to the roof or wall where the line can be brought straight to the diaphragm, and on one or both sides of the diaphragm I connect, by suitable sockets or cavities or supports, a speaking tube or tubes, which pass through the wall of the house into the room or office. By this latter arrangement I am enabled to do away with many of the difficulties attendant on bringing the line-wire around corners to the desired point in the interior of the house. In order to facilitate the turning of angles when the line deviates from a straight course, I employ the following device, namely: A short tube bent at the desired angle is provided with a suitable diaphragm of ebonite, wood, silk, felt, leather, mica, metal, or other material at one or both of its ends, so that the air in the tube conveys the sounds from one diaphragm round the bend to the other diaphragm, and in case the line is also used as an electric conductor to convey electric-bell signals I then carry a light-metal wire from the line on one side of the tube to the line on the other, so as to maintain electric continuity.

When my system of speaking-tube telephones is used for working an exchange system, I use, preferably, flexible tubes for connecting the mouth-piece of one telephone with the mouth-piece of any other telephone in said exchange. The lines from the subscribers may in this case be used for working the annunciators or call-bells electrically. The telephones at the central office may be either within the building, the lines coming in through suitable apertures, or they may be outside the building, as described above, having tubes to bring the sounds to and from the diaphragms to within the office. In this case any two subscribers may be connected by placing the ends of a curved or flexible or other tube over or into or against the ends of the tubes of the two subscribers who desire to be put into communication. The connecting-tube may itself be of metallic materials capable of conducting electricity, or having wound, inserted, or woven into or upon it a suitable wire or strip of metal to conduct electricity, for the purpose of establishing electric continuity between the telephones of two subscribers, the mouth-pieces

of their telephones or of the tubes communicating with them being furnished also with corresponding electrical connections or switches. This arrangement of the system will, therefore, automatically put the call-bell apparatus of any two subscribers into communication at the same moment that they are placed in acoustic communication with one another through the connecting-tube with which their telephones are joined. When several of these pliable connecting-tubes are used, they may be designated by colors, letters, or numbers, so as to facilitate the making of the proper connections.

15 In the drawings, Figure 1 shows the devices for turning corners. Fig. 2 is a general view showing the system. Fig. 3 is a detail. Figs. 4, 5, and 6 are exchange-office arrangements. Fig. 7 is a view of the operator's mouth and ear piece. Fig. 8 shows a subscriber's station. Figs. 9 and 10 are central-office arrangements.

As in other mechanical telephones, the conducting cords or wires A are connected to and supported by diaphragms z , of metal, wood, parchment, felt, or other suitable material, and these diaphragms either form in whole or in part the sides of cases Z, or they close the ends of tubes, which may be either the transmitting, receiving, or turning tubes, as described hereinafter. Between the frame and the diaphragm is interposed an elastic yielding cushion, as india-rubber. The turning tubes E are used for transmitting sound between points when the wires cannot be conducted upon straight lines between the said points, and each tube is therefore constructed to support two or more diaphragms connected to branches of the same line, and is bent or curved, so that the said branches may extend from the turning-tube at an angle to each other, the vibration of one diaphragm being transmitted to the other through the medium of the air confined within the tube. Different forms in which these tubes may be made are represented in Fig. 1, and at the right in said figure is shown a turning tube with a series of diaphragms, the conducting cord or wire being continuous and extending through all the diaphragms which support the line, so that it can take a generally curved direction within the tube without contact with the sides thereof.

The conductor may be a cord saturated with any suitable material to prevent it from being affected by heat or moisture, or it may be a wire; or in some instances, where it is desired to use a cord and at the same time transmit an electrical current, a fine wire, b, may be coiled around the conducting-cord, as shown in Fig. 2. Each transmitter G is suitably supported and provided with a diaphragm, Z, which, however, is not necessarily in immediate proximity to the mouth-piece of the transmitter; but when it is not so arranged a tube, Y, is extended from the mouth-piece to the diaphragm to which the end of the line is connected. This tube Y may be curved or straight, and by its use the vibrations may be

conducted from the mouth-piece to the diaphragm in such manner as to avoid the necessity of curving or turning the conducting-line 70 in order to attach it to a diaphragm adjacent to the mouth-piece.

Where the ear-piece of the receiver must be at some distance from the diaphragm at the receiving end of the line, a conducting-tube, 75 Y', is extended from the point where the ear-piece is situated to the nearest point at which the diaphragm can be placed. An ear-piece, a', may in some instances be upon the end of the tube Y', as shown at the left in Fig. 1; but I prefer 80 to use in connection with the ear-piece a flexible tube, a'', having a metallic ferrule, a³, at the opposite end, adapted for attachment to the end of the tube Y', so that the ear-piece may be attached to any one of a series of tubes 85 Y', the flexible tube a'' bending, so as to permit the ear-piece to be readily applied to the ear of the hearer, and the portable character of the ear or receiving tube enabling the attendant at a receiving-station to put himself in communication with any one of a series of receiving-tubes Y' with the use of but a single ear-tube. I am thus enabled to erect a mechanical switch-board for use in connection with a 90 mechanical telephone at a central station, and to arrange a series of receiving-tubes Y' in much closer proximity upon the support N than would be practicable if each tube Y' was provided with a separate ear-piece. When a 95 series of receiving-tubes are thus arranged in proximity, I may connect any two of them in such manner as to put subscribers upon different lines in direct communication. This temporary communication is effected by means of coupling-pieces C, which may be rigid bent 100 tubes of such form as to permit the opposite ends to be applied to the ends of any two of the tubes Y' that are to be put in communication, as shown in Fig. 3. I prefer, however, to use flexible tubes C, as shown in Fig. 2, each 105 tube being provided at each end with a metallic ferrule, a⁴, adapted for application to the end of the tubes Y'.

Each tube C may have a curved metallic sleeve, a⁵, at or near the center, so as to permit the tube to be suspended to a hook, c, arranged adjacent to the switch-board, as shown in Fig. 9, the free ends of the tube being applied to the different receiving-tubes without 115 detaching the coupling-tube from its support. 120

In Fig. 4 I have shown an arrangement of receiving-tubes supported by a single switch-board, N, which may be used when the wires enter the office from different directions.

When there is a series of switch-boards at 125 one office, and it is necessary to connect the receiving-tube of one board with one of those of another board, I use a connecting-tube, C', extending between the two boards and secured stationary in respect thereto, and in some 130 instances a series of tubes C may be used to secure any desired connections.

In order to call up the subscriber or operator, I use any suitable electric signaling ap-

paratus—as, for instance, an ordinary bell-signal, U—having the usual magneto-generator, as indicated in Fig. 4, by means of which a magneto-current may be sent over the line 5 through the medium of wires wound round the ear-tube or coupling-tube and connected electrically with the conductor A.

When the electrical current is to be transmitted from one conductor to another through 10 the medium of the coupling-tube, a conducting-wire, s, is extended through or wound round the tube and connected with the metallic ferrules a⁴, so that when both of the latter are applied to the receiving-tubes Y' an electrical 15 circuit will be established.

It is of course necessary that when the coupling-tube is disconnected from the receiving-tubes the latter shall be put in electrical connection with the signal—that is, in a circuit 20 therewith—for which purpose I arrange a spring contact-piece, s', adjacent to the end of each receiving-tube Y', so as to normally make contact therewith, all of the contact-pieces s' being connected to the ground-wire s², or otherwise 25 arranged in circuit, and each ferrule a⁴ is provided with a strip of rubber or other electrical non-conductor, e, so arranged as to bear upon the contact-piece s' and thrust it from the receiving-tube when the end of the coupling- 30 tube is applied to that of the receiving-tube, the circuit being thus transferred to the wire carried by the coupling-piece.

It will be evident that other devices and connections may be employed for making the connection 35 between any two conductors when the coupling-tube is applied and for re-establishing the connection between each receiving-tube and the signal when the coupling-tube is withdrawn, and that any suitable signaling apparatus 40 may be used.

In order to facilitate both the transmission and reception of messages at the central office, I in some instances provide the receiving-tube or ear-tube with an ear-piece, b³, and a mouth-piece, a², connected to branches of the same tube, so that when the mouth is applied to the mouth-piece the ear-piece will be in position adjacent to the ear, as shown in Fig. 7, and to support such an appliance in proper position in respect to 45 the signal device U, I may use a bracket, V, supported by the board N, as shown in Fig. 8.

In Fig. 2, M is a microphone communicating with the receiving-tube Y' on one side and on the other side with the mouth-piece of a 55 magneto-telephone, E, the telephone and the secondary coil of the microphone being connected with the line on one side and being grounded on the opposite side by the contact-piece s' and its connections. As a modification 60 of this arrangement a microphone and an electrical telephone may be combined, so that one diaphragm may serve for both.

In Fig. 10 I have illustrated the manner in which my coupling-tubes may be employed 65 for coupling the receiving ends of a series of tubes, which conduct the sound in the same manner as ordinary speaking-tubes, and are

arranged in connection with the central office, so as to constitute a speaking-tube exchange.

Without limiting myself to the precise construction and arrangement of parts shown, I claim—

1. The combination, in a mechanical-telephone system, of a series of conductors extending from subscribers' stations to a central office, a series of tubes arranged in juxtaposition in the central office and each supporting a diaphragm connected to one of the conductors, and a detachable coupling-tube adapted to unite the aforesaid tubes, substantially as 75 described.

2. In a mechanical-telephone system, the combination of a series of conductors extending from subscribers' stations to a central office, a series of tubes arranged in juxtaposition in the central office, and a flexible coupling-tube having terminal rigid ferrules adapted to fit over the ends of the aforesaid tubes, substantially as described.

3. In a mechanical-telephone system, the combination of the receiving-tubes in the central office, two or more switch-boards supporting the receiving-tubes, coupling-tubes, and connecting-tubes C', substantially as described.

4. In a mechanical-telephone system, the combination of mechanical sound-conducting connections and electric conductors extending between the subscribers' stations and the central office, receiving-tubes at the central office, each provided with a diaphragm, and tubular connecting-pieces adapted to said tubes, said coupling-pieces having an electric conductor whereby electric connection is made simultaneously with the uniting of said tubes, substantially as described.

5. In a mechanical-telephone system, the combination of mechanical and electrical conductors extending between the subscribers' stations and the central office, receiving-tubes at the central office, tubular coupling-pieces 100 having electric connections to complete electric circuits between any two of the receiving-tubes, and a separate electric connection between each receiving-tube and the central-office signaling-circuit, substantially as described.

6. In a telephone system, the combination of the receiving-tubes, a contact-piece bearing on each tube and connected with a conductor in the electric circuit, and a tubular coupling-piece adapted to said tubes and having electrical connections to complete electric circuits between any two of the receiving-tubes and having insulating portions interposed between the tube and its contact-piece when connection 115 is made with the coupling-piece, substantially as described.

In testimony whereof I have signed my name to this specification in the presence of two subscribing witnesses.

A. M. ROSEBRUGH.
